UNITED STATES PATENT OFFICE.

PARL O. ECKELS, OF DALLAS, AND RAY DERMONT MONROE, OF ROYSE CITY, TEXAS,
ASSIGNORS TO NU-IDEA MANUFACTURING COMPANY, OF DALLAS, TEXAS, A
CORPORATION OF TEXAS.

CIRCUIT BREAKER FOR MOTOR VEHICLES.

Application filed August 5, 1924. Serial No. 730,196.

To all whom it may concern:

Be it known that we, PARL O. ECKELS and RAY DERMONT MONROE, citizens of the United States, residing, respectively, at Dallas, in the county of Dallas, State of Texas, and at Royse City, in the county of Rockwall and State of Texas, have invented certain new and useful Improvements in Circuit Breakers for Motor Vehicles, of which 10 the following is a specification.

Our invention relates to circuit breakers for motor vehicles; and the object is to provide a safety device for motor vehicles which is controlled by the spark lever for preventing the starting motor from being started by an advance spark and prevents the motor from back-firing, and thus prevents the breaking or locking of any of the starting unit or apparatus which would result from back-firing. Other objects and advantages will be fully explained in the following description and the invention will be more particularly pointed out in the claims.

Reference is had to the accompanying drawings which form a part of this application.

Fig. 1 is a side elevation of the safety device, or circuit breaker. Fig. 2 is a transverse section of the steering column and the spark rod and the fuel control rod with the circuit breaker mounted thereon. Fig. 3 is a plan view of the same shown on broken portions of the steering column and the spark control rod and the fuel control rod. Fig. 4 illustrates the clamp for attaching the circuit breaker to the spark control rod.

Similar characters of reference are used 40 to indicate the same parts throughout the several views.

The drawings show a portion of the steering column 1, a portion of the spark control rod 2, and a portion of the fuel control rod 3 of a motor vehicle. The cable running from the starter switch on the floor of the car to the battery is severed. A bracket clamp composed of members 4 and 5 pivotally connected together at one end 45 by pivot bolts 6 and at the other end by a single bolt 7 and nut 8 is mounted on the steering column 1 and rods 2 and 3 and made rigid therewith. Means are provided 50 for connecting the severed ends of the cable.

The switch starter end 9 is connected to a 55 stationary arm 10 by a contact bolt 11 and insulated from the arm 10 by fibre 12, being secured in place on the contact bolt 11 by suitable nuts. The battery end or terminal 13 is connected to a movable arm 14 which 60 is made rigid with the spark control rod 2 by a clamp 15 which is bolted to the arm 14. The arm 14 is provided with insulation 16 which is mounted on each side of the arm 14 on a contact bolt 17 and secured in place 65 by nuts 18.

The circuit breaker is installed by severing the wire or cable which leads from the starter switch (usually positioned on the floor board) to the battery. The switch end 70 9 of the cable is connected to the arm or point 10 which is rigid with the bracket clamp 4 and 5 by the means above described. The battery end 13 of the cable is attached to the stationary arm 14 which 75 is rigid with the spark control rod 2 as above described. The arm 14 can thus be rocked or vibrated by the spark control rod 2 and the arm 14 is so positioned on the rod 2 that it will be swung back and forth in the cut-out in the clamp member 5. This construction keeps the contact bolt 17 in line with the contact bolt 11, consequently the spark control rod 2 can be used to make contact of the severed ends of the cable. 80

What we claim is,—

1. In a motor vehicle provided with spark and fuel control rods, and a steering column; a circuit breaker for said motor vehicle comprising a bracket mounted on said rods and provided with an arm projecting therefrom, a contact stationary with said arm and bracket and said bracket having means for insulating said contact therefrom, a movable contact, an arm fixedly mounted on said spark control rod for carrying and actuating said movable contact to make connection with said stationary contact, and means for varying the positions of said contacts. 95

2. In a motor vehicle provided with spark and fuel control rods, and a steering column; a circuit breaker for said motor vehicle comprising a bracket mounted on said rods and having a guide slot in one end and an arm stationary therewith and projecting from the other end thereof, a contact 100 adjustably mounted on said arm, a movable

100

105

contact, an arm fixedly mounted on said spark control rod for carrying and actuating said movable contact and adapted to swing in said guide slot, and means for insulating said contact from said arms.

3. In a motor vehicle provided with a steering column, spark and fuel control rods; a circuit breaker mounted on said steering column and consisting of a bracket 10 clamp in two parts pivotally connected together at one end and a bolt pivotally connecting the other ends, a stationary arm struck from the lower bracket member and projected through the upper member, the 15 opposite ends of said bracket clamp mem-

bers having guide slots therein, a contact arm rigidly connected to said spark control rod and adapted to swing in said guide slots, a contact bolt projected through said stationary arm and insulated therefrom, a 20 contact bolt projected through said movable arm and insulated therefrom, said contact bolts being adapted to close a circuit when said movable arm is rocked towards said stationary arm. 25

In testimony whereof, we set our hands, this 19th day of July, 1924.

PARL O. ECKELS.
RAY DERMONT MONROE.
